UNITED STATES PATENT OFFICE.

ELOF THOMAS HEDLUND AND STANLEY EDWARD NOYES, OF PORTLAND, OREGON.

ARTIFICIAL TEETH.

1,332,466.

Specification of Letters Patent.

Patented Mar. 2, 1920.

Application filed September 3, 1919. Serial No. 321,309.

To all whom it may concern:

Be it known that we, ELOF THOMAS HEDLUND and STANLEY EDWARD NOYES, citizens of the United States, residing at Portland, 5 in the county of Multnomah and the State of Oregon, have invented certain new and useful Improvements in Artificial Teeth, of which the following is a specification.

The object of the invention, which relates

10 to artificial teeth of the form commonly mounted on a plate of rubber or other material, is to provide means of holding the plate securely in the mouth, both on the upper and lower jaws.

15 This object is attained by the mechanism illustrated in the accompanying drawing, which forms a part of this specification, and in which:—

Figure 1 is a front elevational view, showing a complete denture, with both upper and lower plates with the teeth in place. Fig. 2 is a side elevational view. Fig. 3 is a plan view of the gold bar and spring attachment.

20 25 Similar numerals refer to similar parts throughout the several views.

In the upper plate 1 and the lower plate 2 are mounted the teeth 3, the numeral 3 referring to all the teeth, in both plates, 30 and forming in connection therewith the ordinary complete denture.

The gold bar and spring attachment 4 is secured to the upper plate 1 at the points 5 5, preferably by being embedded in the 35 material of which the plate is constructed,

and is shaped to conform to the under side of the upper lip by being bent at the point 6. The gold bar and spring attachment 7 for the lower plate 2 is attached to the plate at the points 8 8 and is also shaped to conform to the inside of the lower lip by being bent at the point corresponding to the similar point on the upper plate and designated by the numeral 9.

40 The gold bar and spring attachment 4 is 45 corrugated at the ends 10 10, to insure a secure embedment in the plates 1 and 2, and is provided with the springs 11 11, which may be adjusted to any desired tension.

45 In operation the plates 1 and 2 with the 50 teeth 3 are inserted in the mouth in the usual manner, the spring attachment 4 4 bearing on the gums inside the lips, and being adjusted to give the required amount of tension will hold the plates firmly in place 55 by drawing same securely into contact with the interior of the mouth.

Having thus fully described our invention, we claim and desire to protect by Letters Patent:—

60 In combination, a complete denture comprising both upper and lower plates, a bar and spring attached to each plate and adapted to the shape of the lips and adjustable to give any required tension to draw the 65 plates firmly into contact with the interior of the mouth.

ELOF THOMAS HEDLUND.
STANLEY EDWARD NOYES.
